PLASTIC GABLE TOP CONTAINER
Harry B. Eggleston, Livonia, Mich., assignor to
Ex-Celi-O Corporation
Filed Jan. 6, 1966, Ser. No. 534,257
13 Claims. (Cl. 229—17)

ABSTRACT OF THE DISCLOSURE

An extensible pouring spout closure for a container formed of thermoplastic resinous sheet material wherein the pouring lip area is sanitarily housed by means of a double tear edge seal which may be opened by the initial tearing of a single, easily accessible fused edge seal that in turn initiates, as part of the same operation, the sequential breaking of a pair of independent spout release edge seals.

The present invention relates to packaging, and more particularly to a container of the gable top variety including an extensible pouring spout for liquids and other flowable materials. The innovation finds particular, but by no means exclusive, utility in disposable containers adapted for distribution of milk and other dairy products.

A container of the foregoing character is customarily erected from a flat blank of sheet stock which has been impressed with an appropriate pattern of score lines, the latter defining a plurality of side panels together with corresponding upper and lower panel extension flaps or closure members. The usual procedure in erecting the container is to form the blank into a polygonal tube, open at both ends, and then to close the lower or bottom panel extensions, retaining them in place by means of a suitable adhesive. It is presently the practice to employ paperboard coated with heat and pressure sensitive thermoplastic substances, such as polyethylene, which not only renders the paper sheet material resistant to fluids, but also serves as a sealing adhesive for effecting tight closure and sealing of the container. This sealing action is accomplished by heating the surfaces to be sealed and quickly pressing them tightly together to form a liquid-tight plastic-to-plastic bond.

Although thermoplastic coated containers of the above described type have been commercially successful, there are certain disadvantages connected with their use, one of the most marked of which involves the existence of uncoated raw edges being exposed to the liquid product within the container. Although various methods have been devised to solve the problem of penetration of the liquid product into the paperboard, the result has been an increase in cost of the container, together with the packaging equipment.

A further disadvantage of containers made of thermoplastic coated paperboard sheet material, and having closures which include a pouring lip sanitarily protected therein, is disclosed in U.S. Patent No. 3,120,335, issued February 4, 1964, and assigned to the assignees of the instant invention. As stated therein, when the paperboard blank from which the container is formed is initially prepared, all the surfaces of the container are coated with the thermoplastic material. The pouring lip is thus also coated and, in the event heat is applied directly to the lip surfaces, the lip itself becomes tightly sealed within the closure. When such a container is opened, the lip is apt to become damaged, resulting in objectionable operation and presenting an unsightly appearance. Some means, such as the adhesive coating disclosed in the Patent 3,116,002, is thus required to prevent damage to the pouring lip.

It has long been known that the construction of containers from thermoplastic sheet stock will solve the raw

2

edge penetrating problem. However, applicant is the first to devise an all plastic extensible closure structure wherein the pouring lip area is sanitarily housed within a fused closure while preventing the lip from being sealed in such manner that the lip is apt to become damaged, resulting in objectionable operation and presenting an unsightly appearance. This is accomplished by providing a double tear seal closure. The inner pouring lip edges are welded to provide a first tear seal, while the upstanding ridge panel edges are welded to provide a second tear seal. The result is that the pouring edge and its adjacent areas are completely and sanitarily sealed with the further attainment of a hermetically sealed closure to allow for vacuum packaging.

The thermoplastic substance used is desirably one which is inert to the substance to be packaged, is strong and durable, is inexpensive, and is easy to score and form into containers. One example of such a thermoplastic substance which is useful for packaging dairy products is high-density polyethylene. It will be apparent to those skilled in the art, however, that other heat-sealable materials, that is to say, synthetic plastic material which can be welded together upon the application of fusing heat thereto, will find use under favorable circumstances. Typical materials of this nature are polyvinyl chloride, polyvinyl acetate, vinyl copolymers, polypropylene, polystyrene, cellulose acetate and cellulose acetate butyrate. Sheet material of about 3 to 30 mils thickness are most advantageously employed, depending upon its ability to take and retain a fold.

An object of the present invention is the provision of a new and improved gable top container closure formed of thermoplastic sheet material which will be strong, simple to erect, close and seal, and susceptible of high volume economical production for packaging milk and other comestibles.

Another object of the present invention is to provide a container of the above type having a retractable pouring spout sanitarily housed within an externally heat sealed closure, while preventing the pouring spout from being permanently and inaccessible sealed within the closure.

Still another object is to provide a container of the above character having incorporated into its top end closure an extensible, sanitarily protected spout which may be opened by the initial tearing of a single, easily accessible fused seal that in turn initiates, as part of the same operation, the sequential breaking and simultaneous tearing of a pair of independent spout release fused seals.

A further object of the invention is to provide a container of the above character having a top closure incorporating at opposite ends thereof a pair of extensible sanitarily protected pouring spouts in such manner that either spout may be selectively opened by the user with equal facility, through the application of fingertip forces, to permit dispensing the contents of the container. A related object is to provide a container wherein both spouts may be successively opened by the user to allow for packaging and dispensing non-flowable items.

A final object of the present invention is to provide a method for edge welding the pouring spout of a synthetic plastic container that achieves a hermetically sealed top closure which has excellent release characteristics.

Other objects and advantages of the present invention will become apparent as the following description proceeds, taken in connection with the accompanying drawings, wherein:

FIG. 1 is a fragmentary portion of the outside surface of a flat blank of sheet plastic material showing the inventive structure.

FIGS. 2, 3 and 4 are fragmentary perspective views illustrating sequentially certain of the steps involved in forming the top closure of the container.

FIG. 5 is an enlarged cross-sectional view taken along the line 5—5 of FIG. 4.

FIG. 6 is a fragmentary perspective view of the gable top subsequent to the initial pouring spout sealing.

FIG. 7 is an enlarged cross-sectional view taken along the line 7—7 of FIG. 6.

FIG. 7A is an enlarged partial end view of the initial pouring spout sealing of the container as shown in FIG. 6.

FIG. 8 is a fragmentary perspective view of the gable top prior to the outer sealing.

FIG. 9 is an enlarged cross-sectional view taken along the line 9—9 of FIG. 8.

FIG. 10 is a fragmentary, partially sectioned, perspective view of the assembled and sealed gable top.

FIG. 11 is an enlarged end view of the container of FIG. 10.

FIGS. 12, 13 and 14 are fragmentary perspective views showing sequentially various steps in opening one spout of the container.

While the invention is susceptible of various modifications and alternative constructions, a certain illustrative container closure has been shown in the drawings and will be described below in detail. It should be understood, however, that there is no intention to limit the invention to the specific form disclosed. On the contrary, the intention is to cover all modifications, alternative constructions, equivalents and uses falling within the spirit and scope of the invention as expressed in the appended claims.

Referring more specifically to the drawings, there is shown the outside surface of flat blank 20 (FIG. 1) of thermoplastic sheet material with a pattern of appropriate score lines. The container is separated into three groups by score lines as represented by staggered upper score line 21. The portions of the container blank below score line 21, as seen fragmentarily in FIG. 1, the body group and comprises four side panels, 22 through 25, and a side seam flap 26. The bottom closure group (not shown) is not necessary in the disclosure of the present invention; however, a complete description of one type of structure is given in copending patent application No. 474,869, filed July 26, 1965, now Patent No. 3,334,802, and assigned to the same assignee as the instant application.

The flat blank 20 is defined on the sides by edges 27 and 28, and with the panels being separated by score lines 29 through 32. Integral with the upper ends of the side panels, but separated therefrom by the transverse score line 21, are a plurality of panel extensions which give the top of the container its characteristic gable shape. These panels include a transverse score line indicated generally by the numeral 33, generally parallel to the score line 21 and spaced between score line 21 and the top edge of the blank 20. The areas between score lines 33 and 21 define the roof panels 35 and 37 and the triangular end panels 34, 36 of the top closure, while the areas above score line 33 define the parts of the central rib 69, as shown in the completed closure of FIG. 10.

The roof panels 35, 37 are connected respectively with alternate side panels 23, 25. The upper ends of the roof panels are in turn connected respectively to outer rib panels 38, 39 along the common transverse score line 33. The rib panel 38 terminates in a top flap 40 running along its entire length and connected thereto along a transverse score line 41. By the same token, the outer rib panel 39 terminates in a top flap 42 connected thereto along a transverse score line 43.

The triangular end panels 34, 36 are connected to alternate side panels 22, 24 along the score line 21. The triangular end panel 34 is flanked by triangular foldback panels 44, 45 connected thereto along upwardly converging score lines 46, 47. The downwardly converging or V contour provided by the portions 48, 49 of score line 33 intersect with the score lines 46, 47 at the apex of the panel 34. The panel 45 is also connected to the inclined roof panel 35 along the perpendicular score line 29. A pair of inner rib or pouring spout panels 50, 51

are connected respectively to the foldback panels 44, 45 along their corresponding score lines 48, 49. The panels 50, 51 are connected to each other along a short perpendicular score line 52 extending from the intersection 5 of the score lines 46, 47, 48, 49 upwardly to the edge of the blank. The opposite end of the inner rib panel 51 is connected to the outer rib panel 38 along perpendicular score line 29. By the same token, the triangular end panel 36 is flanked by triangular foldback panels 53, 54 connected thereto along upwardly converging score lines 55, 56. The panels 53, 54 are connected to the inclined roof panels along the perpendicular score lines 30, 31. Inner rib or pouring spout panels 59, 60 are connected to the triangular foldback panels 53, 54 along the downwardly converging portions 57, 58 of transverse score line 33. Panels 59, 60 are connected to each other along short perpendicular score line 61 extending upwardly to the edge of the blank from the intersection of the score lines 55, 56, 57, 58. The opposite ends of rib panels 59, 60 are connected to the roof panels 35, 37 along perpendicular score lines 39, 31 respectively.

Above the point of intersection between horizontal score lines 41, 43 with the perpendicular score lines 29, 30, 31 and 32 there are provided cut lines or slits 62. For the purposes of illustration the slits 62 are shown exaggerated in width while as a practical matter the slits are aligned on their associated score lines 29, 30, 31 and 32 and have an imperceptible width.

It will further be noted that the upper edges 63, 64, 65, 66 of the pour spout panels form a shallow inverted V contour that for the instant embodiment is complementary to the V contour formed by the score lines 48, 49 and 57, 58. The purpose served by the inverted V contour edges 63, 64, 65, 66 will be described later with respect to the formation of the top closure. In contradistinction the top edges 67, 68 extend in a straight line along the top edges of the closure flap panels 40, 42.

The blank 20 of FIG. 1 is adapted to be erected into the completed container C by first folding it upon itself to form a flat tube and adhesively securing the side seam flap 26 to the opposite edge portion of the blank. As the method together with the blank structure utilized to side seam applicant's blank forms no part of the instant invention; any suitable method, such as disclosed in U.S. Patents Nos. 3,085,480 and 3,122,070, may be employed. These patents are assigned to the assignee of the subject application and the disclosures thereof are incorporated by reference for a more complete description of various side seaming methods. While these patents are primarily concerned with side seaming plastic coated paperboard blanks, the manner of attaining a similar surface to surface seal with sheet plastic would be closely analogous.

However, it is also within the contemplation of applicant's disclosure that thermoplastic blanks could be employed wherein no side seam flap, as such, is required. Examples of other possible methods include an edge weld seal made by a hot bar or rotary-type bar applied directly to the blank edges and a "hot knife" type seal performed at the same time the blank is severed from its parent sheet plastic.

Still another extension of applicant's closure would be its utilization with an extruded thermoplastic tube requiring no side seam.

Returning to the instant case of a flattened side seamed blank, the next step is its erection into a tube of substantially square cross-section and a suitable bottom closure, of the type shown for example in previously referred to U.S. patent application No. 474,869, infolded and sealed.

To seal applicant's novel top closure, the parts thereof are infolded into gable form. Depending upon the properties of the particular thermoplastic material and the manner of forming the score lines it may be necessary to pre-bend the triangular panel score lines 46, 47, 55, and 56 by infolding the triangular end panels 34, 36 toward each other as shown in FIG. 2. Again as in the case with

the side seaming operation, numerous methods could be used to score the blank to obviate this step. For example, a thermoforming process could be employed or various cold pressure forming techniques utilized a consequence of which would produce inward movement of panels 34, 35 upon convergence of roof panels 35, 37.

Going to FIG. 3, the closure flaps 40, 42 are pivoted outwardly about their scores 41, 43, respectively toward a horizontal plane. Simultaneously therewith, or as a separate operation, the container is then closed as by passing its top outer rib panels 38, 39 between a pair of converging shoes (not shown) which bring the outer faces of inner rib pour spout panels 50, 51, and 59, 60 respectively together (FIG. 4). In order to insure that the upper edges of the inner rib panels extend above the upper surfaces of flaps 40, 42 a distance substantially equal to the full length of slit 62, it is essential that the shoes or other closing jaws, urge the rib portion, generally shown at 69, into the intimate face contact as shown in FIG. 5.

The inner rib panels 50, 51 are then heat sealed along their upstanding juxtaposed edges 63, 64 while in a like manner the rib panels 59, 60 are heat sealed along their upstanding juxtaposed edges 65, 66, FIGS. 6 and 7 illustrate the container closure after this initial hermetic sealing or welding operation, which is preferably made by a single heater bar having sufficient length and width to encompass the entire area of the upwardly facing edges. As clearly seen in the enlarged cross-sectional view of FIG. 7, there are produced full edge welds 70 and 71 that seal only the edges of the inner rib panels without forming additional unwanted bands or partial seal between the edge welds and adjacent portions of the top closure.

In the instant embodiment the desired edge weld was achieved using high density polyethylene having a thickness of the order of 15 mils. By locating the edges 63-66 approximately .06 inch above the scores 41, 43 (equal to the length of slits 62), it was found that sufficient material is present to allow a single hermetic weld to be formed.

The sealing operation involves lowering a thermostatically controlled hot bar so as to just make contact with the stationary container edges 63-66 and subject them to a temperature of about 225° F. to 250° F. for a dwell time of approximately one second, whereupon the hot bar is moved upwardly and the container is advanced to the next station. The amount of pressure applied to the edges is considered negligible as the thin edge sections will flow almost instantaneously upon contact with the hot bar, while the downward travel of the bar is positively stopped a few hundreds below the initial contact point.

The apparatus for achieving applicant's welded edge closure forms no part of the invention and numerous modifications may be made for heat sealing, such as, for example, impulse sealers or radiant sealers as well as conventional rotary-type bar sealers or band rotary sealers without departing from the scope of the invention.

In order to preclude the formation of a depress or falling away of the pouring spouts adjacent the point P (FIG. 4), with a consequent incomplete weld and likelihood of rupturing under stress, resort is had to the inverted V contour previously noted. This effects a complete seal by providing additional material at the tips of the infolded spouts to insure a substantially horizontal welding area.

By using the above described edge seal of this invention in an extensible pouring spout, the surprising and unobvious discovery was made that the seal tears or separates along a line of weakness included by the vertical plane of centerline 72 (FIG. 7). Hence, the edge weld provides not only an easily formed hermetic weld, attained externally of the filled container, but also insures that the spouts will always remain free and readily accessible in undamaged condition when the user opens the container in the prescribed manner.

In FIG. 9, a partial sectional view of the gable top illustrates the disposition of flaps 40, 42 after being refolded upwardly into vertical substantially coextensive relation with their respective panels 38, 39 to form a pair of sealing flaps extending completely across the container. These sealing flaps have their paired end edges 74, 75 and 73, 76 terminating substantially in the plane of the side walls 24 and 22 respectively. In like manner the paired end edges, indicated at 77 in enlarged FIG. 7A, remaining after the formation of welds 70, 71 terminate in the planes of the side walls 24, 22.

As previously indicated in the above discussion, the points of termination 78 of slits 62 in conjunction with the location of scores 41, 43 below the edges 63, 64 and 65, 66, respectively, are important features in arriving at applicant's easy release hermetic sealed closure. The function to isolate the welding operation and thus prevent "hang up" or "cross blocking" of the pouring spout with consequent difficulty of opening the container. The prevention of partial fusion or welding between the inside surface areas 79 of the sealing flaps 40, 42 and the welds 70, 71 provide a smooth unbroken edge when pouring from the container. It will be noted that sufficient time is provided for the welds 70, 71 to be set by maintaining the rib portion 69 in clamped condition, before flaps are moved to their position shown in FIG. 8.

The container C, as illustrated in FIG. 8, is moved to a final sealing station during which time the rib flaps 40, 42 are closed by closing guides (not shown) providing parallel surfaces on opposite sides of the container top, their configuration bringing the top flaps into position to be urged into their final intimate contact condition (FIG. 8) by the action of clamping blocks (not shown). Preferably, the blocks have faces designed to effect contact of the entire rib surfaces above scores 88, 89 with the exception of chamfered upper and side edge portions of the blocks. The reason for chamfering the block edges is to expose a defined portion adjacent the upper edges 67, 68 and paired side edges 73, 76 and 74, 75 of the rib flaps 40, 42 to achieve a controlled top and end edge weld.

The method of achieving the exposed upper edge weld 81 and end edge welds 82 to complete the hermetic sealing of the container can be by a hot bar similar to the method used for welds 70 and 71. In order to provide one single continuous weld along both the top and sides of sealing rib flaps 40, 42, a single vertically movable hot bar or head heater having a generally inverted U-shaped configuration was employed to simultaneously form the welds 81, 82. However, it is considered within the state of the art to attain the same result by having a hot bar sealer in two or more sections to simultaneously or sequentially achieve the welds 81, 82 without departing from the spirit of the invention.

In order to provide a more pleasing and marketable container the exposed edge welds 81, 82 have been controlled by means of the chamfered block edges together with utilizing the block faces as cold pressure pads. As seen in FIG. 11, a uniform flared weld results while the cold pressure applied by the blocks also prevents warping or deforming of the sealed container rib 69.

Because the exposed side edges 74, 75 of the flaps and 77 of the pour spout panels are substantially coplanar, the side welds 82 can be accomplished during the same dwell period used to form weld 81. In order to insure that the side edges are sealed, the welds 82 should extend approximately $\frac{1}{4}$ inch below the points of termination 78 of the slits 62.

As shown particularly in FIGS. 13 and 14, an extensible sanitarily protected pouring spout 85 of pitcher-like form is incorporated into the top closure of the all plastic container 20 and rendered accessible as a result of the partial severance of the edge welds 81, 82 together with simultaneous and complete severance of edge weld 70 resulting in partial disassembly of the central rib 75 (FIG. 12). This is accomplished by taking advantage of

the angular arrangement of score lines defining the triangular end panels and fold-back panels of the top closure, together with the single plane of weakness, indicated at 72, which includes the controlled severance area of applicant's edge welds 81 and 82 and 70 or 71, depending whether triangular end panel 36 or 34 is used as the pouring spout end of the container.

The pouring spout 85 accordingly comprises the triangular end panel 36, triangular fold-back panels 53, 54, pouring lip panels 59, 60, adjacent portions of outer rib panels 38, 39, and adjacent portions of inclined roof panels 35, 37 (FIGS. 1 and 12-14). The pouring lip panels 59, 60, by virtue of having their edges 65, 66 welded only to themselves, provide the spout 85 with a free and smooth unruptured lip area 80 (FIG. 10) traversed by fluid poured from the container. This area 80 serves as a pouring lip and affords excellent pouring and cutoff characteristics. Moreover, the pouring lip area 80 is completely and sanitarily enclosed by the outer edge welds 81, 82 and the edge welds 70, 71, and the spout is enclosed with complete sanitary protection up to the time the container is opened by the user. Furthermore, by eliminating surface-to-surface heat seals, which are essentially as strong as the original sheet plastic, applicant has provided a closure that may be easily and cleanly separated to open the container and extend the spout 85.

I claim:

1. A container blank of sheet material for providing a tubular-like container of rectangular configuration in 30 horizontal cross-section having a gable-like closure on the top end thereof including a central transverse rib structure when in finalized closed condition, said blank comprising,

- (a) a sheet of material having four side wall panels 35 defined partially by spaced vertically extending score lines and first and second horizontally extending score lines intersecting at generally right angles with said vertical score lines and respectively defining the upper and lower boundaries of said wall panels,
- (b) said vertical score lines extending from the upper edge of the blank to said second horizontal score line,
- (c) said blank above said first horizontal score line defining a closure section including a pair of spaced outer closure panels and a pair of alternately disposed inner closure panels,
- (d) said blank comprising a third horizontal score line spaced upwardly from said first horizontal score line and defining in combining with said vertical score lines integral rib closure panels and pouring lip panels respectively in each of said outer and inner closure panels,
- (e) said rib panels having a fourth horizontal score line spaced upwardly from said third horizontal score line and below its upper terminal edge to provide upper and lower sealing panels, and
- (f) said blank having slit portions on said vertical score lines commencing at the terminal edge of said pouring lip panels and extending at least to the juncture of said fourth horizontal score lines with said vertical score lines, whereby the upper portion of said rib panels are adapted to be folded outwardly along their respective fourth horizontal score lines to allow the pouring lip panels to extend above said fourth horizontal score lines for heat sealing and the pouring lip panel terminal side edges and the rib panel side edges to be heat sealed when said upper rib portions are folded into finalized container form.

2. A container blank in accordance with claim 1, 70 wherein the upper terminal edge of each of said pouring lip panels have an inverted V-contour.

3. A gable top container of foldable thermoplastic sheet material, said container comprising the combination of;

- (a) a tubular body having a bottom closure thereon,
- (b) a pair of opposed roof panels inclined toward each other and overlying said body,
- (c) a pair of opposed end panels infolded between said roof panels from the opposite gable ends formed by the latter,
- (d) two pairs of fold-back panels each pair of which is integral with a respective area of said infolded end panels, said fold-back panels being folded adjacent the undersides of said roof panels,
- (e) a rib panel surmounting each roof panel, each said rib panel formed with a horizontal score line to provide upper and lower sealing panels,
- (f) a pair of pouring spout lip panels joined by a vertical score line and surmounting each pair of fold-back panels and adjoining end panel wherein the upper edges of said lip panels extend above said horizontal score line a defined distance to provide a pair of juxtaposed free side edges,
- (g) a sanitarily protected extensible pouring spout housed in collapsed condition within said container and defined in part by one of said end panels, an adjacent pair of said fold-back panels and an adjacent pair of said lip panels, said spout also being defined by adjacent portions of said roof panels and rib panels,
- (h) said lip panels being folded in generally juxtaposed substantially vertically extending relation with the adjacent pairs of their terminating upper edges only being joined by a first fusion tear seal, and
- (i) said upper sealing panels being folded in juxtaposed substantially vertically extending relation and projecting above said first fusion seals, the terminating upper and side edges of said upper sealing panels being joined by a second fusion tear seal wherein said lip panel side edges and said rib panel side edges forming a common fusion tear seal such that a liquid-tight double tear seal closure is attained.
- 4. A container as defined in claim 3, wherein each said horizontal score line is located substantially intermediate the juncture of said rib panel with its associated roof panel and its upper terminating edge.
- 5. A container as defined in claim 4, wherein said first fusion seal is located above said horizontal score line a defined distance.
- 6. A container as defined in claim 3, wherein said container is semi-rigid in construction such that said edge seals have load bearing capabilities while providing a controlled tear or severance line so that the closure may be subsequently opened to expose the spout.
- 7. A container as defined in claim 3, wherein the upper terminal edge of each pouring lip panel has an inverted V-contour.
- 8. A container as defined in claim 3, wherein each end thereof incorporates an extensible sanitarily protected pouring spout in such manner that either spout may be selectively used.
- 9. A container as defined in claim 3, wherein the height of said pouring lip panels being greater than one-half the height of said rib panels.
- 10. A container as defined in claim 3, wherein:
  - (a) said second fusion tear seal on said side edges extending below said first fusion tear seal on said lip panels.
- 11. A container as defined in claim 3, wherein:
  - (a) said first fusion seal is located above said horizontal score line a defined distance, and
  - (b) the upper terminal edge of each pouring lip panel has an inverted V-contour.
- 12. A container as defined in claim 11, wherein:
  - (a) each end of said container incorporates an extensible sanitarily protected pouring spout in such manner that at least one spout may be selectively used.
- 13. A container as defined in claim 12, wherein:
  - (a) said second fusion tear seal on said side edges ex-
